UNITED STATES PATENT OFFICE

127,650

DESIGN FOR A DRESS

Hattie Carnegie Zanft, Red Bank, N. J.

Application May 15, 1941, Serial No. 100,959

Term of patent 3½ years

To all whom it may concern:

Be it known that I, Hattie Carnegie Zanft, a citizen of the United States, residing in Red Bank, in the county of Monmouth and State of New Jersey, have invented a new, original, and ornamental Design for a Dress, of which the following is a specification, reference being had to the accompanying drawing, forming part thereof.

I claim:

The ornamental design for a dress, substantially as shown.

HATTIE CARNEGIE ZANFT.
